UNITED STATES PATENT OFFICE.

WILLIAM W. DEAN, OF WILMETTE, ILLINOIS, ASSIGNOR TO EFFICIENCY ELECTRIC CORPORATION, OF NEW YORK, N. Y., A CORPORATION OF NEW YORK.

ELECTRICAL PHONOGRAPH DRIVING MECHANISM.

Application filed November 12, 1919. Serial No. 337,518.

To all whom it may concern:

Be it known that I, WILLIAM W. DEAN, a citizen of the United States, residing at Wilmette, in the county of Cook and the State 5 of Illinois, have invented certain new and useful Improvements in Electrical Phonograph Driving Mechanisms, of which the following is a full, clear, concise, and exact description, such as will enable others skilled 10 in the art to which my invention appertains to make and use the same.

My invention relates to electric phonograph driving mechanisms, and more particularly to such mechanisms wherein the 15 phonograph record supporting turntable is caused to revolve by being driven by an electric motor.

One of the objects of my invention is to produce a phonograph power transmitting 20 mechanism which shall be exceedingly quiet in operation and in which contributing causes which would otherwise produce noises of various kinds being herein eliminated or suppressed so that substantially the only 25 noise which may be heard when a phonograph equipped with the driving mechanism of my invention is in operation is that produced by the needle point of the phonograph reproducer which rests upon the rotating record.

Another object of my invention is to provide such an electrically operated motor driven mechanism which will be capable of being cheaply manufactured in quantities 30 without any great variation in the quality of the devices produced. Another object of my invention is to produce such a manufactured device as will remain in adjustment for long periods of time without perceptible 35 adjustment change, and further, to provide means to alter the adjustment of such a mechanism.

Other objects of my invention and the invention itself will perhaps be more apparent 40 by referring to the drawings of an embodiment thereof, forming a part of this specification and in which drawings:

Fig. 1 shows a side view of the mechanism of my invention, in its upright operative position, this view showing the driving mechanism and associated parts as well as an edge 50 of the supporting board and the turntable carried on the top side of the board. In this view a side view of the controlling switch

which has two plunger controlling buttons, 55 and of the speed regulating thumbscrew is had.

Fig. 2 shows an end view of the driving mechanism of my invention, this view being taken from a point at rightangles to the 60 view of Fig. 1.

Fig. 3 shows a schematic circuit diagram of the electrical circuits involved.

Fig. 4 shows a plan view of the speed reducing pinion-and-worm driving link 65 through which motion is communicated from the driving motor to the driven turntable.

Fig. 5 shows a side cross-sectional view of the pinion illustrated in Fig. 4, the turntable, the turntable support, the pinion support and associated parts.

Fig. 6 shows a sectional view of a worm gear secured to the motor shaft, to transmit motion from the motor shaft to the phonograph turntable.

Referring now to the drawings in which like parts illustrated in the different figures are designated by the same reference characters, at M, I show an electric motor, which is preferably of the series wound type, in which the winding and the armature operate in series circuit. This motor is secured by machine screws m, to a metallic support 80 S and which support is secured by machine screws MS—MS to a supporting board B, felt washers being preferably interposed, in each case, between the supporting board and the metallic support.

A phonograph turntable is illustrated at TN being secured to a shaft TS which is adapted to be driven by the electric motor M through the speed reducing mechanical link comprising a worm 15 mounted on the motor shaft 16 and the pinion 17 carried in frictional driving engagement with the said turntable shaft TS. The specific construction and mounting of the pinion and gear members 15 and 17 with their associated parts is important so far as certain phases 90 of my invention is concerned and will be later described in detail.

The ratio of speed reduction accomplished by the worm and pinion to the motor shaft to the turntable shaft is preferably about 15 to 1 so that for a motor speed of 1100 revolutions per minute the turntable shaft is revolving about 78 times per minute. This 100 105

ratio may be altered somewhat when the driving motor is operated at different speeds than at 1100 R. P. M. although I find that, using motors of the standard type, I can at 5 the given motor speed secure very good results in a motor of relatively small size, constructed to operate at a somewhat higher speed.

On the motor shaft 16, I mount a flywheel 10 FW which rotates on the said shaft, and which carries a pair of weighted members 18 and 19 which are normally yieldingly held in normal position by hair-pin springs 20 and 21 respectively. The members 18 and 15 19 are constructed of folded pieces of sheet metal, each being in the form of a bell crank lever, one of the arms of each being weighted, by weights W, secured to the ends of the arms by a machine screw 22, the other 20 arms of these bell crank lever members, extending over the end of the shaft 16, being pivotally held in such position by the hair pin spring members 20 and 21. The axially located ends of the bell crank lever arms are 25 preferably formed somewhat differently so that the arm 23 of the member 18 is lapped over the end of the arm 24 of the member 19. A socket member 25 is carried on the lapped end of the arm 23 having a socket 30 indentation 26 which is regular in shape and highly polished, this socket indentation being arranged in line with the axis of the rotation of the shaft 16.

A toggle pin 27, has one end pressed into 35 engagement with the inner cupped surface of the indentation 26, by the electrical contact controlling spring member 28, which also carries a socket or cupped member 29, having the cupped indentation 30, into which 40 the other end of the toggle pin is placed. Thus the toggle pin is spring pressed between the cups 26 and 30 by the electrical contact controlling spring 28, and when the bell crank lever arm 23 is moved, the motion 45 is transmitted longitudinally of the motor shaft 16, by the toggle pin 27 and the toggle pin will move the spring member 28 to cause it to operate the set of electrical contacts 31. The set of contact springs 50 adapted to be controlled by the contact spring 28, comprises the springs 32 and 33, normally in electrical contact with each other.

Whenever by increased motor speed the 55 toggle pin 27 is moved longitudinally of the shaft and away from the shaft end, motion is thereby transmitted to the controlling contact spring 28 to cause it to force the spring 33, normally resting in electrical contact 60 with the spring 32, away from the said spring 32 so that the electrical contact shown at 31 between the springs, is broken whenever a predetermined speed is exceeded.

The arrangement of the contact springs, is such that normally the contacts 31 on the

springs 32 and 33 are in engagement and this condition prevails for all speeds up to a certain predetermined speed at which the spring 21 is forced outwardly to a sufficient degree that it will contact with the spring 33 to 70 mechanically engage it, whereupon it may, upon increased speeds, carry the spring 33, with it to break the contacts 31.

Referring now particularly to Fig. 3 which shows a schematic diagram of the motor 75 controlling circuits at L¹ and L² show the two incoming line conductors from a source of electric current, not shown, but which source may generate alternating or direct currents such as are commonly used, for instance, for 80 house lighting purposes. I extend these conductors through a suitable switch SW, which is mounted on the upper side of the supporting board as is best illustrated at Fig. 1, and also through a normally short circuited 85 resistance coil RC to the motor M. The resistance coil RC is normally short circuited by the spring contacts 31 whose operation has been previously described, and upon a given predetermined motor speed where at 90 the contacts 31 are opened as before described, the resistance coil RC, is brought to circuit with the motor M, to effect an immediate decrease in the flow of exciting current to decrease the motor speed. 95

I prefer to place the resistance coil RC about the contacts 31, instead of allowing these contacts to open the circuit of the motor entirely, since otherwise, undue sparking at 100 the contacts 31, will cause corrosion of these contacts and a slight hissing noise would be heard. The adjustment of the contact springs may be changed by turning the thrust screw TC, illustrated in Figs. 1 and 2, which has an insulated end bearing 105 against the contact spring 32.

For the purpose of regulating the speed, a thumbscrew ST is located on the upper side of the supporting board B, so as to be 110 convenient of access when the phonograph is in operative condition; this thumbscrew is carried on the end of a long rod SR having at its other end an eccentric cam member EC, the rod SR extending through the moulded insulating block MB, upon which 115 the contact spring set is mounted. A toggle pin TP is carried in a hole extending through a portion of the insulating block MB, the toggle pin being spring pressed against the eccentric member EC by the pressure of the contact spring 32, and the spring 32, when the thumbscrew ST is turned, is moved to different operative adjustment positions, the motion being transmitted through the rod SR, the eccentric member EC, and the linking toggle pin TP. 120

It may be further noted that the insulating block MB contains an assembly of all of the spring contact elements, the spring contacts and contact adjusting elements being 125

an unitary piece of apparatus which may be placed on the underside of the supporting board B, with the rod SR extending through a hole in the board, whereupon the 5 thumb adjusting screw ST may be screwed on to the end of the rod SR. By this improved arrangement for conveying motion from the centrifugal rotating members to the spring contacts, I am enabled to operate 10 electrical contacts responsive to a predetermined motor speed, without the necessity of providing such expedients as, for instance, collector rings with brushes and the like, which are objectionable in practice for 15 various reasons; I have furthermore provided a unitary piece of apparatus which is capable of being easily and reliably adjusted while in use and which may be easily removed as a unit for inspection and re- 20 pairs.

The subject matter of the governing mechanism disclosed herein is claimed in my co-pending application, Serial No. 473,569, filed May 31, 1921, the claims here- 25 in being confined to other features of the pre-disclosed construction.

Referring now particularly to Fig. 5, in which a cross-sectional view is shown of the vertical shaft TS carrying the turntable TN, 30 and also of the co-operating elements, comprising supporting elements and motion transmitting elements, at S, is shown a portion of the metallic support to which the various parts are secured and which support 35 is fastened to the under side of the supporting board B, as before described. At BG is illustrated a metallic bridge member, which may be a die casting, for holding the various motion transmitting elements and 40 insuring their correct alignment. This member is illustrated also in Figs. 1, 2, and 4. A hole is drilled vertically through the metallic support S and a portion of the bridge member BG to admit the shaft TS, the 45 walls of this hole forming a bearing surface for the rotatable shaft. A tube member TB having a flanged head FL, is adapted to be fitted over the lower end of the shaft which contains a transverse slot. This tube member 50 TB has a pin SP extending diametrically through it and which pin is adapted to be straddled by the end of the shaft TS, when the turntable, with the turntable supporting shaft, is placed in operative position, the pin SP then fitting within the 55 transverse slot TG to key the shaft to the tube member TB.

A sleeve SL is slid over a section of the tubular portion of the bridge BG which 60 forms a bearing BB for the turntable shaft, and also over a section of the tubular member TB, having preferably the same outside diameter, and a small set screw 41, permanently secures the sleeve SL in position. This sleeve SL is required to main-

tain the position of the tubular member TB, in case the turntable TN should be removed from the phonograph, the tubular member in such case then being held in place by being joined through the sleeve SL with the 70 tubular portion of the bridge member BG.

At GB is shown the thrust bearing supporting portion of the bridge member BG, being provided for the purpose of forming an end support and bearing for the vertical 75 rotating parts which move with the turntable TN, comprising the shaft TS with its co-operating elements. The portion GB of the bridge, has a hole drilled vertically through it, this hole being drilled at the 80 same time and by the same operation, when the hole which forms the bearing BB in the upper part of the bridge is drilled, a similar bearing GG being formed in the lower bridge portion, for the rotatable shaft RS, 85 frictionally connected to the turntable shaft TS, and which rotates with it when the phonograph is in ordinary use, as will be readily understood from the description which 90 follows.

The shaft RS is supported on a bearing-ball 42 which is axially located by a bearing cup intermediate in the end of the shaft RS. This ball rests, as illustrated, upon a smooth end plane surface of the machine 95 screw 43, although this surface may be cupped also if desired. The screw 43 is adapted to be longitudinally adjusted so as to raise or lower the turntable TN and all intermediate rotating parts including the 100 pinion PN. The pinion PN is carried between the end flange FL of the tubular member TB and the end flange EF of the rotatable shaft RS, journaled in GB. Two felt washers 44 and 45 are placed one on each 105 side of the pinion PN to frictionally clamp it; a center pin 46 is mounted in the end of the shaft RS, and passes through the said felt washers and the said pinion PN, being of sound insulating material or of 110 metal of small diameter, which may in the latter case, carry a sound non-conducting insulation between it and the joined pinion.

The pinion is adapted to center the pinion PN, and being made of very small diameter or of material which is a non-conductor of sound vibrations or both, will not convey to an appreciable extent, "gear noise" vibrations from the pinion PN to the metallic bridge BG through the shaft RS. The 115 felt washers 44 and 45 not only subdue the tendency of the pinion to vibrate, giving grating noise, but prevent such noise producing vibrations as may possibly be had, under extreme conditions, from being communicated to the metallic supports and to the turntable shaft TS.

I find that in most of the devices of the art hereto produced, that the turntable, being of relatively large diameter and rela- 120 125 130

tively small thickness acts as a phonic diaphragm, and sound vibrations conducted by the turntable shaft to the center of the turntable, produce considerable sound vibrations in the turntable, which acting as a diaphragm communicates to the air amplified vibrations, creating an unpleasant and disturbing noise effect.

In the device of my invention, I there-
10 by provide a "floating" pinion which is insulated from the turntable, so far as sound vibrations are concerned, and the pinion itself is damped by the clamping felt washers on either side of the pinion so that
15 the tendency of the pinion to produce high frequency vibrations is practically eliminated.

To communicate motion to the pinion PM, I provide a worm-gear 15, secured on
20 a projecting end of the motor shaft 16, the worm-gear engaging the teeth of the pinion PN so that the pinion may be driven thereby. This worm gear is, as is best illustrated in Fig. 6 in the form of a hollow
25 tube carried on an extension 47, of the motor shaft 16, and which extension is of reduced cross-section. The worm-gear tube 15 is insulated from the shaft 16 and the reduced end thereof, by felt washers 49 and 50 and
30 a bushing of sound insulating material, which may be also of felt, 51. By the provision of this sound insulating material, I so cushion the rotatable gear 15, that no sudden blows may be struck by the helical
35 thread 61, thereof, against the co-operating teeth of the pinion PN, when the motor is operating, and any vibrations which might otherwise be set up between these two movable parts, are subdued to a degree amounting
40 to practical elimination.

A thrust bearing ball 62, is placed between the clamping nut 48 on the worm gear carrying shaft, and a fixed longitudinally adjustable stationary thrust member, herein illustrated as a machine screw 64. The machine screw 64 is carried on a projecting arm 65, of the rigid metallic bridge G, and when properly adjusted places the shaft in proper operative position so that the armature will
50 have such a position as will align it magnetically with the motor field poles, and it is held in such a position by a set nut, 66, which set nut must be loosened whenever the longitudinal adjustment of the shaft is
55 to be changed. The clamping nut 48 on the end of the pinion shaft is adapted to so clamp the worm gear 15 so that it will be tightly held on the shaft 47 and will, at all times, rotate with it.

60 The engaged pinion PN, adapted to be driven by the worm 15 however, is preferably only frictionally held between the clamping felt washers 44 and 45. By this means, I enable the operator of the phonograph to stop the revolving turntable for

the purpose of placing thereon or removing, or both, phonograph records, this being accomplished without stopping the electric motor which will continue to rotate the pinion PN, but the frictional engagement of which with the clamping felt washers on either side, is not sufficient to cause the stopping of the motor when the turntable TN, is held against motion, or to cause the motor M to exert a considerable 70 turning effort on the turntable shaft TS, as might otherwise inconvenience the operator who attempts holding the turntable still.

By the long bearing BB for the turntable shaft TS, and the method of assembly, herein specifically set forth, I am able to rotate the turntable TN, regularly without any dipping of one edge or other of the turntable as it rotates, due to a lack of 75 proper alignment of the various moving or related parts.

Having thus described my invention, I wish to state that I am aware that numerous and extensive departures may be made from the embodiment herein illustrated and described, but without departing from the spirit of my invention; my invention is defined in the following claims.

I claim:

1. In a phonograph mechanism, the combination with a phonograph motor, a rotatable turntable, a turntable supporting shaft, a motor shaft, interconnecting means for communicating rotary motion from the said motor to the said shaft, said interconnecting means comprising an intermediate yielding member of relatively sound non-conducting material, a governing mechanism for the said motor, a moving member therefor adapted to be vibrated by rapidly changing motor speeds, said non-sound conducting intermediate member being disposed between the said governor movable member and the said turn-table shaft. 100

2. In a phonograph, the combination with a phonograph motor, a turntable, a turntable shaft, a motor shaft speed reducing means for communicating motion from the motor shaft to the said turntable shaft, said speed reducing means comprising a motor shaft member and a turntable shaft member, each member being mounted on its respective shaft, one of the said members having yielding frictional engagement with its shaft, the last said member being insulated from its shaft by sound insulating means. 110

3. In a phonograph, the combination with a phonograph motor, a turntable, a turntable shaft, a motor shaft speed reducing means for communicating motion from the motor shaft to the said turntable shaft, said speed reducing means comprising a motor shaft member and a turntable shaft mem- 120

ber, each member being mounted on its respective shaft, one of the said members having yielding frictional engagement with its shaft, one of the said members being insulated from its shaft by sound insulating means.

4. In a phonograph, the combination with a phonograph motor, a turntable, a turntable shaft, a motor shaft speed reducing means for communicating motion from the motor shaft to the said turntable shaft said speed reducing means comprising a motor shaft member and a turntable shaft member, each member being mounted on its respective shaft, one of the said members having yielding frictional engagement with its shaft, both of the said members being insulated from their respective shafts by sound insulating means.

5. In a phonograph, the combination with a turntable, a turntable shaft, said turntable shaft comprising two separable sections, one of the said sections being non-removably secured to the said turntable, a driving pinion carried on the other shaft section, means to cause the two shaft sections to enter into driving engagement with each other, a frame member, shaft bearings in the said frame and each of the said sections in longitudinal alignment, a motor, a motor shaft, a bearing in the said frame for the said motor shaft and a speed reducing gear member in driving connection with the said motor shaft, said member engaging the said pinion.

6. In a phonograph, the combination with a phonograph motor, a shaft therefor, a turn-table, a turn-table shaft, a worm gear carried by the said motor shaft, a gear pinion adapted to be driven by the said worm gear, a friction clutch connecting the said pinion with the said turn-table shaft, said friction clutch comprising opposing clutch faces and an intermediate disc of relatively non-sound conducting textile material, said material being impregnated with oil.

7. In a phonograph mechanism, the combination with a phonograph motor, a shaft therefor, a turntable shaft, a worm gear carried by the said motor shaft, a gear pinion adapted to be driven by the said worm gear, motion communicating means connecting the said pinion with the said shaft, said means comprising a section of relatively sound non-conducting material.

8. In a phonograph mechanism, the combination with a phonograph motor, a shaft therefor, a turntable shaft, a worm gear carried by the said motor shaft, a gear pinion adapted to be driven by the said worm gear, motion communicating means connecting the said pinion with the said shaft, said means comprising a section of relatively sound non-

conducting material, a supporting frame for the said motor, an auxiliary frame member carried by the said supporting frame, said shaft being journaled in the upper portion of the said auxiliary frame, a thrust bearing at the end of the said motor shaft, said thrust bearing comprising an adjustable member carried by the said auxiliary frame.

9. In a phonograph mechanism, the combination with a phonograph motor, a shaft therefor, a turntable shaft, a worm gear carried by the said motor shaft, a gear pinion adapted to be driven by the said worm gear, motion communicating means connecting the said pinion with the said shaft, said means comprising a section of relatively sound non-conducting material, a supporting frame for the said motor, an auxiliary frame member carried by the said supporting frame, said shaft being journaled in the upper portion of the said auxiliary frame, a thrust bearing at the end of the said motor shaft, said thrust bearing comprising an adjustable member carried by the said auxiliary frame, a shaft supporting the said gear pinion, said gear pinion shaft, and said turntable shaft being aligned axially, said gear pinion shaft being journaled in the lower portion of the said auxiliary frame.

10. In a phonograph mechanism, the combination with a phonograph motor, a shaft therefor, a turntable shaft, a worm gear carried by the said motor shaft, a gear pinion adapted to be driven by the said worm gear, motion communicating means connecting the said pinion with the said shaft, said means comprising a section of relatively sound non-conducting material a supporting frame for the said motor, an auxiliary frame member carried by the said supporting frame, said shaft being journaled in the upper portion of the said auxiliary frame, a thrust bearing at the end of the said motor shaft, said thrust bearing comprising an adjustable member carried by the said auxiliary frame, a shaft supporting the said gear pinion, said gear pinion shaft, and said turntable shaft being aligned axially, said gear pinion shaft being journaled in the lower portion of the said auxiliary frame, a thrust bearing at the end of the said motor shaft, said thrust bearing comprising an adjustable member carried by the said auxiliary frame, a shaft supporting the said gear pinion, said gear pinion shaft, and said turntable shaft being aligned axially, said gear pinion shaft being journaled in the lower portion of the said auxiliary frame, and an adjustable shaft end supporting bearing comprising a bearing ball supporting the lower end of the said pinion shaft.

11. In a phonograph mechanism, the combination with a phonograph motor, a shaft therefor, a turntable shaft, a worm gear carried by the said motor shaft, a gear pinion adapted to be driven by the said worm gear, motion communicating the said pinion with the said shaft, said means comprising a section of relatively sound non-conducting material, a supporting frame for

the said motor, an auxiliary frame member carried by the said supporting frame, said shaft being journalled in the upper portion of the said auxiliary frame, a thrust bearing at the end of the said motor shaft, said thrust bearing comprising an adjustable member carried by the said auxiliary frame, a shaft supporting the said gear pinion, said gear pinion shaft, and said turn-table shaft being aligned axially, said gear pinion shaft being journalled in the lower portion of the said auxiliary frame, and an adjustable shaft end supporting bearing comprising a bearing ball supporting the lower end of the said pinion shaft, and means for axially adjusting the said pinion

shaft, said adjusting means being carried in the said auxiliary frame member.

12. In a phonograph, the combination with a phonograph motor, a turn-table, a turn-table shaft, a worm gear carried by the said shaft, a gear pinion adapted to be driven by the said worm gear, a friction clutch connecting the said pinion with the said turn-table shaft, said friction clutch comprising opposing clutch faces and an intermediate disc of relatively non-sound conducting material.

In witness whereof, I hereunto subscribe my name this 10th day of Nov., A. D. 1919.

WILLIAM W. DEAN.
